UNITED STATES PATENT OFFICE.

JOHN H. STONEMETZ, OF GRAND HAVEN, MICHIGAN.

PRINTING-PRESS.

No. 890,467.

Specification of Letters Patent.

Patented June 9, 1908.

Application filed December 26, 1907. Serial No. 408,216.

To all whom it may concern:

Be it known that I, JOHN H. STONEMETZ, a citizen of the United States, residing at Grand Haven, in the county of Ottawa and State of Michigan, have invented certain new and useful Improvements in Printing-Presses, of which the following is a specification.

My invention relates to improvements in printing presses, and its objects are: First, to greatly facilitate the spreading and proper distribution of the ink upon the forms. Second, to provide a means whereby the amount of ink to be used may be easily regulated.

I attain these objects by the mechanism illustrated in the accompanying drawing, in which

Figure 1 is an elevation of a portion of the end of a printing press that carries the inking mechanism. Fig. 2 is a top plan of the same. Fig. 3 is an end view of the same with the ink table and ink well shown in section on the line $y-y$ of Fig. 1. Fig. 4 is a front elevation of the actuating cam and its attachments. Fig. 5 is a side elevation of the same. Fig. 6 is a sectional elevation of one side of the press frame on the line $z-z$ of Fig. 1. Fig. 7 is a side, and an edge view of the lever that controls the supply of ink to the rollers. Fig. 8 is a top plan of the lever and sheave that actuate the distributing ink rollers longitudinally. Fig. 9 is a detached view of the fountain or feed roller and the frame that supports it. Fig. 10 is a plan of the actuating cam showing the lever attachments.

Similar letters refer to similar parts throughout the several views.

1 represents a portion of the frame of a printing press and 2 represents the reciprocating bed that carries the form of type when printing.

My invention consists of the manner of actuating the fountain roller 3', the ink distributing rollers 3, 4, 4', and the form inking rollers 5 5', which is as follows: The cam 20 is mounted upon the shaft 3", upon which the fountain roller 3' is mounted, in such a manner that the turning of the cam will not turn the fountain roller except as the pawl 21' engages the ratchet wheel 21. The pawl 21' is pivotally secured to the guide 19 which, in turn, is firmly secured to the cam 20, so that when the cam 20 is made to oscillate, by the action of the crank 11, and the connecting rod 10 upon the arm 12, the shaft 3" and the roller 3' will be made to revolve a little with

each revolution of the crank 11, so that the ink contained in the ink well 16 will be taken up by the roller 3' and afterwards taken up and carried to position to be distributed on the top of the ink table 2' by the action of the guide 19 upon the roller 18" which carries the arm 18 and the roller 3 up with each backward, and down with each forward oscillation of the cam 20, so that the roller 3 is carried, alternately, to position to receive ink from the roller 3' and distribute it upon the ink table for further distribution by the rollers 4 4' before being carried, by the ink table, to the form inking rollers 5 5'.

The amount of ink taken up by the roller 3, from the roller 3', is governed by the position of the lever 17, thus: With the lever 17 in the position indicated by the solid lines in Figs. 1 and 5, the lug 17" on the body 17', will be situated so far back of the pawl 21 that the pawl will not come in contact with it at any portion of its movement, as the cam 20 is oscillating, but if the lever 17 is carried down to the position indicated by the dotted lines in Fig. 5, the lugs 17" will be carried forward so that the pawl 21' will engage it when carried backward and be held up so that it will not engage the ratchet wheel 21 until it has passed some distance upon its forward stroke, thus not carrying the shaft 3" and the roll 3' as far as when the lever is in position to allow the pawl to engage the ratchet wheel further back, as hereinbefore described. The pawl 21" is pivoted to the frame 1 and is designed to engage the ratchet wheel 21 and hold it against the backward movement of the pawl 21', and the pawl e is also pivoted to the frame 1 and is designed to hold the lever 17 to the desired position.

The rollers 4 4' are made to revolve by friction upon the surface of the ink table 2 as it reciprocates upon the frame 1 and, for the purpose of distributing the ink evenly, the rollers 4 4' and 5' are made to reciprocate lengthwise as follows: The shaft 9 is journaled in boxes 9', attached to the frame 1. This shaft has three arms, 7', 8 and 15, firmly mounted upon it, and one arm, 7, loosely mounted upon it. The arm 8 has an anti-friction bearing b mounted upon it in position to be engaged in the groove f in the cam wheel 20, which groove is made to traverse the surface of the cam wheel diagonally so that as the cam wheel is made to oscillate, as hereinbefore described, the movement of the

bearing *b* in the groove *f* will cause the shaft 9 to oscillate and to carry the arms 7' and 15 with it, and the bearing *b'* on the arm or lever 7 engages the groove *f'* in the surface of the cam wheel 20, which groove is so formed, diagonally of the surface of the wheel, that the upper end of the lever 7 will be carried to the right when the arms 7' and 15 are carried to the left, and vice versa. The upper ends of the levers or arms 7 and 7' are provided with antifriction bearings *a a* that are fitted to engage the groove in the periphery of the sheaves 6 6, which are secured to the ends of the shafts that carry the rollers 4 4' so that the oscillating motion of the shaft 9 is transmitted, by means of the arms 7 and 7', to the rollers 4 4' to cause said rollers to reciprocate, alternately, in opposite directions, thus tending to distribute the ink that is carried by the roller 3 to the ink table. As the bed 2 passes back under the type inking rollers 5 5 these rollers take up a portion of the ink that has been distributed upon the ink table and carry it to the roller 5' and this roller is made to reciprocate lengthwise by the segment 15' engaging the flange 14, as indicated in Figs. 1 and 6. The segment 15' is so formed that even though the roller 5' is so placed in its bearings that the flange 14 does not engage the notch in the periphery of the segment, the movement of the segment, caused by the oscillating motion of the shaft 9 will, invariably, carry the segment to position so that the flange 14 will drop into the notch before the complete revolution of the press is made. For the purpose of rendering the rollers 5 5 adjustable I form slots *d d* through the side pieces of the frame 1 and pass the bolt *c''* through them, securing them to place by means of the nuts *c c* above the frame and *c' c'* below the frame, in such a manner that if it is desired to move the rollers sidewise this can be done by simply loosening the nuts *c' c'* and sliding the boxes or bearings to the position desired, and if it is desired to raise or lower the rollers, this may be done by properly manipulating the nuts *c c, c' c'* up or down as desired. In Fig. 2 I have shown the ink table 2 cut away at each side of the rollers 3 3' and the roller 3 cut away to show its relative position with the roller 3', and by this means I have been able to disclose the position of the ink well 16 whence the ink is taken up by the roller 3' and spread over the surface of the roller 3, by which roller it is carried up and distributed over the surface of the ink table 2, as hereinbefore more fully described. The arms 18 that carry the roller 3 are securely attached to the shaft 18' which shaft passes through the frame 1 under the ink well 16 in such a manner that the arms 18 18 must act simultaneously to hold the roller 3, at all times, in direct alinement with the

roller 3' and with the surface of the ink table 2'.

Having thus fully described my invention, what I claim as new, and desire to secure by Letters Patent of the United States, is:

1. In combination with a printing press and its ink rollers, an oscillating cam wheel, a shaft journaled to the press frame, an arm securely attached to said shaft and an arm loosely mounted on said shaft for actuating the ink distributing rollers longitudinally, bearings upon these arms engaging the wheel, arms securely mounted upon the shaft with one end engaging flanges on the end of the ink rollers, and a pawl and ratchet connected with the cam wheel to actuate the ink roller below the ink table.

2. In combination with a printing press, its frame, reciprocating bed and ink rollers, an oscillating cam wheel, a shaft journaled upon the frame, an arm securely mounted upon the shaft and an arm loosely mounted upon the shaft, a bearing on each of said arms and engaging the cam wheel, the loose arm extending beyond the cam wheel and arranged to cause one set of ink rollers to reciprocate longitudinally, arms securely mounted on the shaft and connected to cause other sets of ink rollers to reciprocate longitudinally, a shaft carrying the cam wheel, an ink roller mounted on said shaft, a ratchet wheel mounted on said shaft adjacent to the cam wheel and revoluble therewith, a guide mounted with the cam wheel, a shaft mounted in the frame, arms mounted on said shaft, an ink roller mounted on said arms, a roller on the arms to engage the guide that is connected with the cam wheel to raise and lower said arms.

3. In combination with a printing press, its frame, bed and ink rollers, an oscillating cam wheel, a shaft revoluble in said cam wheel, an ink roller on said shaft, a ratchet wheel mounted on the shaft, a guide mounted with the cam wheel, a pawl mounted on said guide and engaging the ratchet wheel, a lever mounted on the shaft and having a lug for regulating the action of the pawl upon the ratchet wheel, and arms carrying an ink roller and having a roller engaging the guide to raise and lower the ink roller.

4. In combination with a printing press, its frame, bed, and ink rollers, an oscillating cam wheel, a shaft carrying said cam wheel and revolubly mounted therein, an ink well mounted on said shaft, a guide and pawl mounted with the cam wheel, a ratchet wheel mounted on the shaft and engaged by the pawl, a lever mounted on the shaft and having a lug in position to regulate the action of the pawl upon the ratchet, arms pivoted at one end to the frame, an ink roller revolubly mounted in the other ends of the arms in position to be actuated by the guides on the cam wheel to cause the said roller to

oscillate in a vertical plane, a shaft journaled to the frame, arms mounted thereon and engaging the cam wheel in such a manner as to be made to oscillate at right angles therewith, arms mounted on this shaft and connected with the ink rolls causing them to reciprocate as the shaft oscillates.

5. In combination with a printing press and its frame, bed and ink rollers, the upper 10 side pieces of the frame having slots therein, an oscillating cam wheel mounted on the frame, a shaft journaled on the frame and made to oscillate by the cam wheel, arms on said shaft connected with the ink rollers to 15 cause them to reciprocate as the shaft oscillates, bearings adjustably mounted in the

slots in the frame, form ink rolls mounted in said bearings, a longitudinally reciprocating distributing roller mounted over said form inking rollers, an arm mounted on the shaft 20 and having a segment at its upper end with a notch in position to engage the reciprocating distributing roller and cause it to reciprocate as the shaft oscillates, substantially as shown and described.

Signed at Grand Rapids Michigan December 21, 1907.

JOHN H. STONEMETZ.
